UNITED STATES PATENT OFFICE.

LUDWIG MANTLER, OF ST. LOUIS, MISSOURI.

WRAPPER.

No. 926,270.

Specification of Letters Patent.

Patented June 29, 1909.

Application filed September 21, 1908. Serial No. 454,083.

To all whom it may concern:

Be it known that I, LUDWIG MANTLER, a citizen of the United States, residing at St. Louis, State of Missouri, have invented certain new and useful Improvements in Wrappers, of which the following is a full, clear, and exact description, reference being had to the accompanying drawings, forming a part hereof.

10 My invention has relation to improvements in package-wrappers; and it consists in the novel construction of wrapper more fully set forth in the specification and pointed out in the claims.

15 In the drawings, Figure 1 is a plan of the outer face of a blank from which the wrapper is formed; Fig. 2 is a face elevation of the wrapper folded over four sides of a box or package, parts being broken away; Fig. 3 is 20 a perspective of the box with wrapper partially folded against the ends of the box; Fig. 4 is a perspective of the box showing one end of the wrapper partially sealed; Fig. 5 is 25 a perspective of the box showing one end of the wrapper fully sealed; and Fig. 6 is a detail section on the line 6—6 of Fig. 1.

The object of my invention is to provide any conventional form of paper or other wrapper for boxes or packages containing 30 food products such as flour, meal, cereals, and the like, which are liable to be attacked by insects, or germs, or be materially affected by moisture which may set up fermentation, or equivalent chemical action within the 35 body of the material confined in the package, with means which shall serve as an effective barrier against ingress of germs, insects, and other influences into the body of the package, such barrier consisting in the presence 40 at the seams of the wrapper of a suitable composition which is impervious to such germs and insects, and not affected to any material extent by moisture or changes of temperature or variations in atmospheric 45 conditions.

The composition here referred to is disposed on the wrapper in close proximity to the usual adhesive with which the blank is provided and by which the seams of the 50 wrapper from which the package is constructed, are sealed.

The advantages of the invention will be better apparent from a detailed description thereof which is as follows:—

55 Referring to the drawings, and for the present to Fig. 1 thereof, said figure repre-

sents a paper or other blank or sheet from which the wrapper is formed, the blank being foldable over any conventional form of six-sided box or package. The blank is composed of sections 1, 2, 3, 4, 4', 5, and 6, each section covering its corresponding face of the package about which the blank is wrapped, the blank folding along the several dotted lines shown in the figure. The figure represents the outer face of the blank as wrapped about the package as will be clearly apparent by reference to the remaining figures of the drawings. Disposed along the edges of the terminal sections 5, 6, are strips of adhesive 65 or glue *a*, *a*, a similar pair of adhesive strips or layers *a*, *a* being disposed along the edge of one of the sections 4 (complementary to section 4'). These adhesive layers *a*, *a* in each case are spaced apart, the intervening 70 space being provided with a composition *b* superposed over a layer of paraffin or wax *c*. To the composition of the layer *b* either alone or in conjunction with the bottom layer *c*, the virtue of my invention is attributable. 75 The layer *b* is composed of resin mixed with sufficient oil or equivalent diluent or solvent to impart thereto the consistence of a paste or mucilage and is then spread on the previously applied layer of paraffin *c*. The 80 layer *c* is merely to prevent the resin and oil mixture from penetrating the fiber of the paper, the paraffin being unaffected by the composition of the layer *b*. The oil which I prefer to mix with the resin is olive oil, though 85 it is to be understood that I do not confine myself specifically thereto, since any suitable inorganic, or organic oil, animal or vegetable, volatile, or fat oil, capable of forming an emulsion or paste with, or effecting a partial 90 solution of, the resin may be employed. This layer *b* (having resin as a base) is effective in resisting the ingress of germs and insects into the package, and while itself forming a harmless composition, yet at the same 95 time it is germ-proof, insect-proof, to a degree water-proof, and not materially affected by changes in temperature. For temperate climates a lower per cent of resin would be employed than in hot countries, the composition being apt to flow in a hot climate if the 100 percentage of oil were too great.

In practice, the blank as shown in Fig. 1 is first turned over and one face of the package or box *B* is placed over section 1 of the blank; this constitutes say, the bottom of the package as finally wrapped. The sections 2, 3

are then brought up against the sides of the box, and then the sections 4, 4' are brought in overlapped relation against the face opposite the section 1 (Fig. 2), the section 4' being 5 lapped over the strips *a*, *b*, *a* of the complementary section 4, and pasted thereto. It may be stated that the layer *b* will adhere to the strip 4' as well as the glue-strips or layers *a*, *a*, but of course the primary sealing is supposed to be done by the glue, that of the strip *b* being in a measure but secondary. In the next step of the operation the end sections 5, 10 6, opposite the overlapped complementary sections 4, 4' are folded against the end of the box B, (Fig. 3) leaving the composition layers *a*, *b*, *a* in position to be engaged by the ends of the overlapped sections 4, 4' which are accordingly folded down and cemented to the ends 5, 6 (Fig. 4) leaving two triangular 15 projections which are finally glued down to the folded ends 4, 4' (Fig. 5) when the wrapper is complete. Of course, in practice any kind or form of wrapper will answer and the present is only one example out of many. In all 20 cases however, the resinous layer *b* must be so disposed along the glued seams that it will serve as a barrier to the ingress of insects, germs and the like. Glue and similar adhesives (*a*, *a*) do not have the property of intercepting germs, and insects, but there is something about the composition of resin which has such a result. Since therefore no germs or insects can gain access to the interior of the 25 wrapper they will be effectively barred from entering the package or box B and the contents of the latter may be kept fresh for a considerable length of time.

Having described my invention, what I claim is:—

- 40 1. A wrapper blank or sheet provided with sealing means, and a suitable germ-proof composition disposed on the same surface with the sealing means in conjunction with and in juxtaposition to, such sealing means.
- 45 2. A wrapper blank or sheet provided with suitable adhesive for sealing the same, and a composition having a resin base disposed on the same surface with the adhesive in conjunction with and in juxtaposition to, 50 said adhesive.

3. A wrapper for packages composed of a sheet having suitable adhesive for sealing the same about the package, and provided with a compound of resin and fat oil on the same surface with the adhesive in conjunction with and in juxtaposition to, said adhesive. 55

4. A wrapper blank or sheet provided with suitable adhesive for sealing the edges of the same, a layer of paraffin disposed on the same surface contiguous to said adhesive, and a coating of a compound having a resin base spread upon the paraffin. 60

5. A wrapper blank or sheet having a pair of adhesive bands or strips disposed contiguous to its edges for sealing the same, and a coating of resinous compound disposed between the adhesive bands for the purpose set forth. 65

6. A wrapper blank or sheet having a pair of adhesive bands or strips disposed contiguous to its edges for sealing the same, a layer of paraffin disposed between the adhesive bands and a coating of a compound of resin and a suitable diluent spread over the 70 paraffin. 75

7. A wrapper blank or sheet having a pair of adhesive bands or strips disposed contiguous to its edges for sealing the same, a layer of paraffin disposed between the adhesive bands, and a coating of a plastic mixture of resin and a fat oil spread over the 80 paraffin. 85

8. A package wrapper formed of a sheet sealed at the edges, and provided with germ-proof composition in close relation to the adhesive sealing said edges and on the same surface therewith. 85

9. A wrapper blank or sheet having a pair of adhesive bands or strips disposed contiguous to its edges for sealing the same, a layer of paraffin disposed between the adhesive bands, and a plastic coating of resin and olive oil spread over the paraffin. 90

In testimony whereof I affix my signature, 95 in presence of two witnesses.

LUDWIG MANTLER.
